UNITED STATES PATENT OFFICE.

FRANK WIBERLEY, OF JAMAICA, NEW YORK, ASSIGNOR TO BARTHELS MANUFACTURING CO., OF BROOKLYN, NEW YORK, A CORPORATION OF NEW YORK.

DESIGN FOR A TIP FOR LACES.

47,551.

Specification for Design.

Patented July 6, 1915.

Application filed June 3, 1914. Serial No. 842,789. Term of patent 14 years.

To all whom it may concern:

Be it known that I, FRANK WIBERLEY, a citizen of the United States, and resident of Jamaica, Long Island, county of Queens, State of New York, have invented a new, original, and ornamental Design for Tips for Laces, of which the following is a specification, reference being had to the accompanying drawing, which illustrates a tip showing my new design in plan view.

The tip is tapering in form and relatively

of extremely small diameter throughout and comprises a beaded portion and a continuing tapering smooth free end portion.

I claim:

The ornamental design for a tip for laces as shown and described.

FRANK WIBERLEY.
